UNITED STATES PATENT OFFICE.

ALLEN O. NIEDLANDER, OF INDIANAPOLIS, INDIANA, ASSIGNOR OF ONE-HALF TO GEORGE H. MILLER, OF SAME PLACE.

CAR-COUPLING.

SPECIFICATION forming part of Letters Patent No. 391,719, dated October 23, 1888.

Application filed June 21, 1888. Serial No. 277,761. (No model.)

To all whom it may concern:

Be it known that I, ALLEN O. NIEDLANDER, of Indianapolis, county of Marion, and State of Indiana, have invented certain new and useful Improvements in Car-Couplers; and I do hereby declare that the following is a full, clear, and exact description thereof, reference being had to the accompanying drawings, in which like letters refer to like parts.

10 My invention relates to the construction of car-couplers, and will be understood from the following description.

In the drawings, Figure 1 represents a top view of my device, showing the ends of two cars coupled. Fig. 2 is a side view of the same on a larger scale. Fig. 3 is an end view showing the hooks dropped down.

15 In detail, *c* represents a car, and to each end of this is connected a coupler, which consists 20 of a shank, *sh*, made of any suitable material, having buffers *b* formed integral therewith, each of these buffers being provided with a draw-bar, *d*, with a spring, *sp*, near the rear, as shown in Fig. 2. These buffers have openings 25 through which passes a rod, *r*, having levers *l* formed at each end.

It will be understood that between the four buffers there are three openings, as shown in Fig. 1, and in the outer one of these openings, 30 upon the rod *r*, are hooks *h*, which are preferably formed integral with the rod, and are in any event rigidly connected thereto. The center opening in Fig. 1 is left without any hook, but in Fig. 3 is shown another hook, *h'*, 35 loosely mounted on the rod, which is intended to be used in case one of the other hooks breaks.

The device operates as follows: By means of the lever *l* the hooks *h* are thrown up and 40 backward in position for coupling on each car. When the cars are brought together by means of the levers *l*, the hooks are thrown down, so as to couple over the rod of the adjacent car in the manner shown in Fig. 1. The hook *h'* 45 being loose on the rod *r* hangs down out of the way and may be raised by hand when it is necessary for use; but, as said before, this loose hook is only to be used in case of accident, when one of the outside rigid hooks *h* is broken or

twisted so that it will not operate. If there 50 were no means provided for such an emergency, the strain would be altogether upon the hook at the opposite end, but the central hook, *h'*, being loose on the rod *r*, may be slipped along and coupled upon the rod of the adjacent car, and it will hold firmly and relieve 55 the other hook from the additional strain.

The lever *l* may be made long or short, as desired. In the drawings it is shown so that it may be operated by the brakeman from the side of 60 the car without going between the cars, or, if desired, this lever may be carried up along the side of the car and have a hand-wheel upon the top and be operated from the top of the car, or it may be connected by means of a chain 65 in any of the well-known ways.

I do not intend to limit myself to the use of any number of these rigid or loose hooks, nor 70 to a lever of any peculiar shape or length, as it will be readily seen that with a slight mechanical change it may be made to operate from the top of the car, if desired.

The number of buffers and springs may be varied to suit the economy or the desire of the car-builder, my invention consisting in operating 75 one or more rigid hooks mounted on a rod which passes through the ends of the buffers by a lever either at the side or from the top of the car.

It will be seen that by this construction the 80 car is always firmly held in line with that which precedes it, and in going around a curve, where the tendency is for the flange of the inner wheel to hug the tread of the rail and the flange of the outer wheel to pull away from 85 its rail, it will be seen that the grip of the outer hook is tightened while that of the inner hook is loosened, and the result is to draw the flange of the wheel away from the inner rail, and thus relieve the friction at that point and to 90 draw the other wheel of the car toward the outer rail, thus insuring much greater ease and freedom of movement and making it easier for the engine to pull the load.

What I claim as my invention, and desire to 95 secure by Letters Patent, is the following:

1. A car-coupler comprising two or more buffers, *b*, rod *r*, passing through these buffers,

having two or more hooks, *h*, rigidly connected to such rod, with means, such as levers *l*, connected at the outer ends of the rod for operating the hooks to couple and uncouple the 5 cars, substantially as shown and described.

2. A car-coupler composed of the rod *r*, carrying outer rigid hooks, *h*, a central hook, *h'*, loosely mounted on such rod, and a lever, *l*, at the end thereof, such rod passing through buff-

ers connected to the end of the car, substantially as shown and described.

In witness whereof I have hereunto set my hand this 16th day of June, 1888.

ALLEN O. NIEDLANDER.
